SELF-ADJUSTING GLOVE-STRETCHING FORM.

1,259,119.

Specification of Letters Patent. Patented Mar. 12, 1918.

Application filed March 12, 1917. Serial No. 154,108.

To all whom it may concern:

Be it known that we, ANDREW K. MARTELL and FRANK WATERFIELD, citizens of the United States, and residents of Los Angeles, 5 in the county of Los Angeles, State of California, have invented certain new and useful Improvements in Self-Adjusting Glove-Stretching Forms, of which the following is a specification.

10 Our invention relates primarily to a form for use in cleaning gloves and the object thereof is to provide a device for this purpose which can be easily and quickly inserted within the glove to be cleaned, which 15 will automatically adjust itself to the size of such glove and which will hold the glove in its natural shape while being cleaned and while drying.

A further object is to provide a device of 20 this character which will be cheap and simple in construction and which can be easily and quickly positioned for use or withdrawn from its position of use without injury or damage to the glove.

25 Other objects and uses will appear herein-after and while we have shown, and will describe our preferred form of construction and operation it will be understood that we do not limit ourselves to such form or construction or operation, but that various 30 changes and adaptations may be made in either the construction or operation, or both such construction and operation without departing from the spirit of our invention.

35 We accomplish these objects by the device described herein and illustrated in the accompanying drawings forming a part hereof in which:

Figure 1 is a front elevation of our complete form.

40 Fig. 2 is a side elevation of Fig. 1.

Fig. 3 is a section on the line 3—3 of Fig. 1.

45 Fig. 4 is an enlarged detail of the thumb hinge.

Fig. 5 is an enlarged detail of a modified form.

50 Referring to the drawings our form comprises substantially a sheet metal glove, divided longitudinally of its width into a back member 10 and a front member 11, the adjacent edges of said members being spaced apart a short distance for a purpose hereafter described.

55 Near the upper end of each finger portion

of the back and front members respectively are provided sockets 15 and 16 which register with each other and have mounted there-in the free ends of a V-shaped connector spring member 17, with the closed end thereof extending inwardly, and near the lower end or wrist portion of said members are similar sockets 18 and 19 and in these sockets are mounted the ends of a V-shaped connector spring member 20 with the apex 60 thereof extending inwardly. The ends of these connector members project through said sockets a short distance and are bent after being positioned to prevent accidental displacement. It will be noticed that these 65 springs serve the double purpose of connecting the parts together and of furnishing the required expansive means for stretching the glove when positioned thereon. These springs are initially formed of a size and 70 shape sufficient to hold the device at its extreme expanded position, which position will be somewhat larger than the size of the glove it is intended to be used with, so that any 75 size of glove within its limits when mounted 80 thereon will be always held under tension.

Mounted upon the front member in the usual position is a thumb member. This thumb member is divided longitudinally in a plane parallel with the plane of division 85 of the back and front members, into a front member 12 and a rear member 13, said rear member being connected to the front member 11 by a hinge 14, (best shown in Fig. 3).

Like sockets and connector springs are 90 provided for the thumb members. Back member 10 has provided centrally thereof and midway its length a socket 25 in which is mounted a spring member 26, the ends 27 and 28 of which bear against the inner op- 95 posed face of front member 11. This last spring may be omitted if desired. A locking tongue 29 is formed in the wrist portion of the front member by slitting both sides and one end of a narrow strip and then bending 100 the strip thus formed inwardly at right angles and forming a V-shaped catch 30 on the free end thereof. A similar locking strip 31 is formed in the wrist portion of the back member and has the free end thereof bent 105 upwardly to form a catch 32 for engagement with catch 30 whereby when the front and back portions are drawn together, catch 30 will ride over catch 32 and hold the device 110 in its closed position, it being understood

that these locking members will be sufficiently rigid to hold the parts against the strength of the connector springs.

In Fig. 5 we have shown a modified form 5 of connection. In this form we secure on the inner face of the finger portion a stud 35 and on the opposed face of the other member we provide a socket 36 adapted to slidably receive said stud, and a coil spring 37 10 is coiled around said stud and socket to provide means for expanding the form.

In operation when it is desired to insert the form within a glove to be cleaned, the form will be compressed between the thumb 15 and fingers of the operator, or in any other suitable manner. The fingers will then be inserted within the fingers of the glove to be cleaned. The thumb member will then be moved on its hinge to the position shown 20 in Fig. 2 and the thumb of the glove drawn thereon. The balance of the glove will then be drawn over the form the form will then be released and the spring members will cause the form to expand until the glove is 25 stretched to its normal shape and size. After the glove has been washed or otherwise cleaned the form may be hung with the open end upward by means of the perforations in the wrist portion.

30 Suitable clamping means may be provided for clamping the form in its closed position if found desirable.

Having described our invention what we claim is:

35 1. As a new article of manufacture a glove form comprising a back member and a front member, mounted in parallel relation but spaced apart, flexible means connecting said members together in a normally expanded position; and a thumb member hingedly connected to one of said members.

40 2. A glove stretcher comprising a form in the shape of a glove, said form being composed of two members, one of said members being the back and the other the front portion thereof, said portions being mounted in parallel relation and yieldably connected together but spaced apart whereby 45 said members may be moved toward each other for insertion within a glove; and flexible connections between said portions.

55 3. A glove stretcher comprising a form in the shape of a glove, said form being composed of a front and a back member, yieldably connected together but spaced apart; yieldable connections between said members adapted to normally hold said members in their spaced relation; and a 60 thumb member hingedly connected to said front member, said thumb comprising a front and a back member yieldably connected together but spaced apart; and flexible connections between said thumb members adapted to normally hold the same in

their spaced relation; and means to hold said first mentioned members in their collapsed position.

4. As a new article of manufacture a glove stretcher comprising a front and a back member mounted in parallel relation but spaced apart; flexible connections between said members adapted to hold said members in their spaced parallel relation; a thumb member hingedly connected to said 75 front member, said thumb member comprising two parallel members adjustably connected together.

5. A self adjustable glove stretching form comprising a front member and a back member connected together in parallel relation but spaced apart; flexible connections between said members, whereby said members are adapted to be moved toward each other; a thumb member hingedly secured to said front member, said thumb member comprising parallel front and back members spaced apart and flexible connections therebetween.

6. As a new article of manufacture a glove form comprising a substantially hollow form in the shape of a glove, said form being composed of two members each comprising one half of said form and being spaced apart; flexible connections between 95 said members whereby said members may be drawn toward or away from each other.

7. As a new article of manufacture a glove stretching form comprising a hollow casing substantially glove shaped, said casing being composed of a front and a back member each forming substantially one half of said casing but spaced apart; spring connections between said front and back members adapted to normally hold said members spaced apart; a thumb member hingedly mounted on said front member.

8. As a new article of manufacture a glove stretching form comprising a hollow casing substantially glove shaped, said casing being formed of a front and a back member each forming substantially one-half of said casing; spring connectors between said members adapted to normally hold said members spaced apart a short distance and to permit the same to be drawn toward each other; a thumb member hingedly connected to said front member, said thumb member being composed of a front and a back member; and spring connectors 115 between said members.

9. As a new article of manufacture, a glove form comprising a back member and a front member mounted parallel to each other but spaced apart; connecting means 125 for said members adapted to retain said members in parallel relation and to normally hold said members spaced their maximum distance apart and to permit variation of said spaced relation; and a thumb 130

member pivotally mounted upon one of said members.

10. As a new article of manufacture a glove form comprising a back member and a front member mounted parallel to each other but spaced apart; connecting means for said members adapted to permit relative transverse movement only, and to normally

hold said members in their maximum expanded position; and a thumb member pivotally mounted upon one of said members. 10

In witness that we claim the foregoing we have hereunto subscribed our names this 28th day of February, 1917.

ANDREW K. MARTELL.
FRANK WATERFIELD.
